(57) **CLAIM**

The ornamental design for a camera, as shown and described.

DESCRIPTION

FIG. 1 is a perspective view of a camera showing a first embodiment of our new design;

FIG. 2 is another perspective view thereof;

FIG. 3 is another perspective view thereof;

FIG. 4 is another perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is a perspective view of a camera showing a second embodiment of our new design;

FIG. 12 is another perspective view thereof;

FIG. 13 is another perspective view thereof;

FIG. 14 is another perspective view thereof;

FIG. 15 is a front view thereof;

FIG. 16 is a rear view thereof;

FIG. 17 is a left side view thereof;

FIG. 18 is a right side view thereof;

FIG. 19 is a top view thereof;

FIG. 20 is a bottom view thereof;

FIG. 21 is a perspective view of a camera showing a third embodiment of our new design;

FIG. 22 is another perspective view thereof;

FIG. 23 is another perspective view thereof;

(Continued)

FIG. 24 is another perspective view thereof;

FIG. 25 is a front view thereof;

FIG. 26 is a rear view thereof;

FIG. 27 is a left side view thereof;

FIG. 28 is a right side view thereof;

FIG. 29 is a top view thereof; and,

FIG. 30 is a bottom view thereof.

The dashed broken lines illustrate portions of the camera that form no part of the claimed design. The dot-dash broken lines define the bounds of the claimed design and form no part thereof.

1 Claim, 30 Drawing Sheets
